CASING PUSHER

Melvin A. Dannehl, Boise City, Okla., assignor to Continental Oil Company, Ponca City, Okla., a corporation of Delaware

Application February 20, 1956, Serial No. 566,421

1 Claim. (Cl. 254—29)

This invention relates generally to improvements in the art of well drilling, and more particularly, but not by way of limitation, to an apparatus for pushing cylindrical members such as casing and drill pipe into a restricted well bore.

In geophysical prospecting it is frequently necessary to drill shot holes in areas where sand, gravel and boulders are encountered, particularly in the sedimentary portion of the shot holes. Such strata tend to cave in the walls of the bore hole, both while the bore is being drilled and in the process of loading dynamite in the hole. As a result, the usual procedure is to set a casing through the sedimentary portion of such a shot hole or bore to facilitate drilling the bore below the sedimentary portion, and to prevent caving in of the walls of the bore while the shot hole is being loaded with dynamite.

During the operation of lowering a casing through such a shot hole, the lower end of the casing frequently contacts a restricted portion of the bore where the walls of the bore have already caved in. In such an event it is necessary to force the casing through the restricted portion of the bore. Various methods have heretofore been used to push the casing downwardly. Perhaps the most efficient method heretofore known was by the use of a jar hammer. This operation was accomplished by lifting a large weight (such as 200 pounds) with the hoisting line of the drilling apparatus and then dropping the weight on top of the casing. It will be apparent that the only instant a substantial force is applied to the casing by the use of such a process is at the instant the weight contacts the upper end of the casing. Therefore, such a method is slow and tedious and frequently resulted in failure; thereby necessitating pulling the casing and starting over, or, if the bottom of the casing was below the sedimentary formation, cutting off the casing to approximately ground level.

The present invention contemplates a novel clamping apparatus whereby the drive rod of the drilling unit, which is usually operated by hydraulic pressure, can be applied directly to the casing. The apparatus of this invention utilizes a pair of pivotally supported clamps for securely contacting opposite sides of the casing or other cylindrical member, whereby a substantial downward force may be imposed through the clamps to the casing. The clamps are supported in such a manner that the downward force may be applied to the casing with a minimum tendency for pivoting or bending the casing, whereby the casing may be forced through a shot hole in a substantially true vertical direction. Also, the apparatus of this invention may be easily arranged along the casing by the hoisting line of the drilling unit for making a new bite or engagement with the casing to further force the casing into a well bore or shot hole.

An important object of this invention is to generally improve well drilling operations.

Another object of this invention is to facilitate the lowering of casing through a restricted shot hole or well bore.

2

A further object of this invention is to impose the maximum available force on a casing being lowered through a restricted shot hole.

Another object of this invention is to minimize the bending of a casing being forced through a restricted shot hole, whereby the casing is pushed in the desired downward direction.

A still further object of this invention is to provide a simply constructed casing pushing apparatus which may be economically manufactured.

Other objects and advantages of the invention will be evident from the following detailed description, when read in conjunction with the accompanying drawings, which illustrate my invention.

In the drawings:

Figure 1 is a perspective view of my novel casing pusher.

Figure 2 is an elevational view of the casing pusher shown in operating position on a casing during a pushing operation.

Figure 3 is an elevational view of the casing pusher being raised upwardly along a casing for the purpose of reengaging the casing and further pushing the casing into a well bore.

Broadly stated, the present invention may be defined as an apparatus for transmitting a downward pushing force to a vertically extending cylindrical member, comprising a pair of parallel side beams secured in spaced relation, a pair of opposed clamping jaws pivotally secured between and at one end portion of said beams, said jaws being spaced to receive the cylindrical member therebetween and to clamp said member when the opposite end portions of said beams are forced down with respect to said jaws, and a push plate secured to said opposite end portions of said beams for receiving the downward pushing force, said push plate being secured at an angle to remain substantially horizontal when said jaws engage the cylindrical member.

Referring to the drawings in detail, and particularly Fig. 1, reference character 4 generally designates my novel casing pusher which has a pair of parallel side beams 6. The side beams 6 are arranged in spaced relation to receive and support a pair of opposed clamping jaws 8 and 10 therebetween.

The foremost or forward clamping jaw 8 is rigidly secured on a pair of arms 12 which extend forwardly from the jaw along the adjacent or inner sides of the beams 6 toward the ends 14 thereof. A pin 16 extends transversely through the arms 12 and the side beams 6 adjacent the ends 14 to pivotally support the arms 12 and the forward jaw 8. The pin 16 has a handle 18 on one end thereof to facilitate removal of the pin. The opposite end of the pin 16 may be supported in any desired manner in the opposite side beam 6, such as by the use of a threaded nut or cotter pin (not shown).

The opposite clamping jaw 10 is rigidly supported on a pair of arms 20 which extend rearwardly from the jaw along the side beams 6. Another pin 22 extends transversely through the side beams 6 to pivotally support the arms 20. The pin 22 is preferably permanently secured to the side beams 6, and in spaced relation to the pin 16, to position the clamping jaws 8 and 10 loosely around a casing or the like when the arms 12 and 20 extend horizontally along the side beams 6 as illustrated in Figure 1, and as will be more fully hereinafter set forth.

A hook or eye 24 is secured to the upper surface or crown of the pin 22 about half way between the beams 6 for receiving a hoisting line 34 of the drilling unit (not shown) to facilitate raising the apparatus 4.

A push plate 26, preferably in the form of a channel, is secured between the side beams 6 rearwardly of the pin 22 and extends beyond the rear ends 28 of the side beams 6. It is to be observed that the push plate 26 extends

at an angle and through an imaginary plane which projects below the pins 22 and 16.

Operation

In lowering a casing 30 (see Fig. 2) through a typical well bore or shot hole 32, the casing 30 will frequently contact a restricted portion (not shown) of the well bore 32; whereupon the casing 30 will not move downwardly through the well bore 32 by its own weight. In that event, the casing pusher 4 may be installed on the casing 30 in the manner illustrated in Fig. 2 to transmit a downward force from the drilling apparatus to the casing 30.

To install the apparatus 4 on the casing 30, the forward pin 16 is removed from the side beams 6 to permit removal of the forward clamping jaw 8 and arms 12. The side beams 6 may then be placed transversely or laterally over the casing 30 until the rearward clamping jaw 10 contacts the side of the casing. Whereupon the clamping jaw 8 is placed in contact with the opposite side of the casing 30 and is secured between the side beams 6 by reinserting the pin 16. It is preferred that the clamping jaws 8 and 10 are of a size—and the pins 16 and 22 are spaced—such that the clamping jaws 8 and 10 loosely surround the casing 30 when the side beams 6 extend at right angles to the casing 30.

The usual drive rod (not shown) of the drilling apparatus is then lowered into contact with the push plate 26 to pivot the side beams 6 into the position illustrated in Fig. 2. As the side beams 6 are pivoted to lower the rearward ends 23 thereof, the clamping jaws 8 and 10 are wedged or forced into contact with the opposite sides of the casing 30. It is preferred that the size of the clamping jaws 8 and 10, with respect to the casing 30, is such that the push plate 26 extends substantially horizontal when the clamping jaws are in tight engagement with the opposite sides of the casing. Therefore, when the downward force on the push plate 26 is continued, the drive rod will exert a vertically downward force on the push plate 26 and will not have a tendency to wedge the apparatus 4 toward the casing 30. Also, the downward force exerted by the drive rod will have a minimum tendency to bend the casing 30, thereby effectively transmitting the downward force of the drilling unit to the casing 30.

When the apparatus 4 has been forced downwardly into proximity with the ground level, or to the lowest extent desired, the hoisting line 34 of the drilling apparatus is secured to the eye or hook 24 and the drill rod is raised above the push plate 26. The hoisting line 34 is then pulled upwardly to raise the apparatus 4 along the casing 30. It will be observed that the eye 24 is positioned at approximately the center of gravity of the apparatus 4, whereby the side beams 6 will tend to pivot back into a horizontal position when an upward force is exerted on the hoisting line 34.

As the beams 6 are moved into their horizontal positions, the clamping jaws 8 and 10 pivot on the pins 16 and 22 until the arms 12 and 20 extend horizontally along the side beams 6. The jaws 8 and 10 will then again extend loosely around the casing 30 and slide along the casing 30 as the apparatus 4 is raised.

In the event a further pushing of the casing 30 is desired or required, the hoisting line 34 is stopped when the apparatus 4 has been raised to the desired extent. The drive rod is then again lowered into contact with the

push plate 26 to pivot the side beams 6 and lower the ends 23, to again bring the clamping jaws 8 and 10 into engagement with opposite sides of the casing 30. The hoisting line 34 is then disconnected from the eye 24, or slackened, and the force imposed by the drive rod on the plate 26 is continued to again force the casing 30 downwardly in the well bore 32.

The action of the apparatus 4 may be supplemented by periodically dropping a weight on the upper end of the casing 30 in the manner previously described. However, the use of the apparatus 4 alone is all that is ordinarily required to force the casing 30 into the well bore 32.

The apparatus 4 may be removed from the casing 30 either by raising the apparatus 4 until it slips off of the upper end of the casing, or by removing the forward jaw 8 in the manner previously described and moving the apparatus 4 laterally from the casing. It will be apparent that the apparatus 4 may be used on various sizes of casing or other cylindrical members merely by changing the sizes of the clamping jaws 8 and 10.

From the foregoing it is apparent that the present invention will improve well drilling operations and particularly the completion of shot holes for geophysical prospecting. By use of the present invention, the lowering of casing through a restricted shot hole or well bore will be materially facilitated, since the maximum available force may be imposed upon the casing. The casing will be forced in substantially a true downward direction with a minimum of bending of the casing. It will also be apparent that the present apparatus is simply constructed and may be economically manufactured.

Changes may be made in the combination and arrangements of parts as heretofore set forth in the specification and shown in the drawings, it being understood that changes may be made in the precise embodiment shown without departing from the spirit and scope of the invention as set forth in the following claim:

I claim:

An apparatus for transmitting a downward pushing force to a vertically extending cylindrical member, comprising a pair of parallel side beams secured in spaced relationship, a pair of opposed arcuate clamping jaws, a pair of parallel spaced arms for each of said jaws, each arm being secured at one end to one of said jaws, a pair of pins, extending transversely through said beams, one pin extending through one end of each pair of said arms to pivotally secure said pair of clamping jaws to said pair of parallel beams, a push plate secured to said beams externally of said jaws for receiving a downward pushing force, said push plate being secured at an angle to remain substantially horizontal when said jaws engage the cylindrical member, one of said pair of pins being removable and securing the outer jaw of said pair of clamping jaws between said side beams, and a lifting hook secured to the other of said pair of pins for raising the apparatus along the cylindrical member.
